(57) **CLAIM**

The ornamental design for a coating film transfer tool.

DESCRIPTION

FIG. 1 is a front view of the coating film transfer tool;
FIG. 2 is a rear view thereof;
FIG. 3 is a top view thereof;
FIG. 4 is a bottom view thereof;
FIG. 5 is a right side view thereof;
FIG. 6 is a left side view thereof;
FIG. 7 is a sectional view thereof taken along line 7-7 of FIG. 1; and,
FIG. 8 is a sectional view thereof taken along line 8-8 of FIG. 1.

1 Claim, 6 Drawing Sheets

FIG. 1

FIG. 2

FIG.3

FIG.4

FIG. 7

FIG. 6

FIG. 5

FIG. 8
